CLAIM

The ornamental design for a monitor patch, as shown and described.

DESCRIPTION

FIG. 1 is a perspective view of a monitor patch;
FIG. 2 is a front view of the monitor patch;
FIG. 3 is a rear view of the monitor patch;
FIG. 4 is a top view of the monitor patch;
FIG. 5 is a bottom view of the monitor patch;
FIG. 6 is a left side view of the monitor patch;
FIG. 7 is a right side view of the monitor patch;
FIG. 8 is an exploded perspective view of the monitor patch;
FIG. 9 is a perspective view of the monitor patch showing an unclaimed rectangular pad;
FIG. 10 is an exploded perspective view of the monitor patch showing an unclaimed rectangular pad;
FIG. 11 is a perspective view of the monitor patch showing an unclaimed circular pad; and,
FIG. 12 is an exploded perspective view of the monitor patch showing an unclaimed circular pad.

The broken lines in FIGS. 5, and 8–12 depict unclaimed portions of the monitor patch and form no part of the claimed design.

1 Claim, 12 Drawing Sheets
